UNITED STATES PATENT OFFICE.

JOHN ROUSSEAU, OF DETROIT, MICHIGAN, ASSIGNOR OF ONE-HALF TO
PETER MARTIN, OF SAME PLACE.

COMBINATION OIL-CAN AND OILSTONE-COVER.

SPECIFICATION forming part of Letters Patent No. 618,483, dated January 31, 1899.

Application filed October 9, 1897. Serial No. 654,708. (No model.)

To all whom it may concern:

Be it known that I, JOHN ROUSSEAU, a citizen of Canada, residing at Detroit, in the county of Wayne and State of Michigan, have 5 invented certain new and useful Improvements in a Combination Oil-Can and Oilstone-Cover, of which the following, taken in connection with the accompanying drawings, is a full, clear, and exact description.

10 The object of my invention is to devise an oil-containing cover for an oilstone that will feed the oil down onto the stone by simply pressing a button or similar device and which will be extremely simple in operation and of 15 economical construction.

To these ends my invention consists in the device constructed and arranged substantially as set forth hereinafter.

Referring to the accompanying drawings, 20 Figure 1 is a perspective view of the cover. Fig. 2 is a perspective view of the cover taken from the bottom. Fig. 3 is a longitudinal vertical section of the can.

The cover or lid is formed of a box A of 25 rectangular shape. C is a sheet-metal box of the width of the interior of the box A, but of less length and depth than its interior. This box C has extensions c and e on opposite ends. The projection c enters a notch c' in the cover 30 A, and the projection e is engaged by the spring d, by which means the oil-box is securely held in the cover. The bottom of the box has an opening b, that has a cork valve s attached to the end of the lever p. This lever p is mounted upon a suitable support q, secured to the bottom of the box B. A spring 35 u passes around the pivot r of the lever p and over the valve s, holding it tightly closed. To the other end of the lever p is secured a rod n, projecting through an opening in the 40 top of the box. Said opening has a tube h soldered thereto extending into the box around the rod n. A cap closes the bottom

of the tube, having a hole therein for the rod n to work in. A spiral spring i surrounds 45 the rod n and rests on the bottom of the tube h. Over this spring is a washer j, and on this, and sliding in said tube is a cork valve k. Over this another washer l. A button or head a is secured to the extremity of rod n, and 50 between this button and washer l is a tube m. The tube h has a small opening o in it near to its attachment to the can. This hole will be normally closed by the cork valve k; but when the button a is depressed the rod n de- 55 presses the valve k, so that the hole o is left exposed and the air is free to enter the box C at the same time that the outer end of the lever p is raised, carrying the valve s with it, and thus leaving the oil free to run out through 60 the opening b.

For filling the can a threaded cylinder is 65 secured to one end of the can and has a screw-cap f fitting therein, with a leather washer g to keep it tight.

What I claim is—

In an oil-containing cover for an oilstone, the combination of the trunnions q, the lever p, mounted therein, the valve s secured to one end of lever p for closing the hole b, the 70 spring u for holding the valve s closed, the rod n, mounted on the end of lever p, the cylinder h secured to the can having hole in bottom through which the rod n passes; the spring i on rod n, resting on bottom of cylinder h, the cork valve k on rod n, the washer l between spring i and cork valve k, the head a on rod n, the tube m on rod n, the washer l, between the tube m and cork valve k; the tube h having a hole o near the cover normally 80 closed by cork valve k, substantially as set forth.

JOHN ROUSSEAU.
